United States Patent Office

Des. 202,974
Patented Nov. 23, 1965

202,974

ADVERTISING SIGN

Herbert C. Rosenthal and Saul Bass, Los Angeles, Calif.,
assignors to Hunt Foods and Industries, Inc., Fullerton,
Calif., a corporation of Delaware

Filed Mar. 1, 1965, Ser. No. 84,002

Term of patent 14 years

(Cl. D1—12)

FIG. 1.

FIG. 2.

FIG. 3.

FIG. 6.

FIG. 1 is a perspective view of an advertising sign embodying our new design;

FIG. 2 is an elevational view thereof;

FIG. 3 is an enlarged top plan view thereof;

FIG. 4 is a perspective view of a modified form of the advertising sign illustrated in FIGS. 1 through 3;

FIG. 5 is a perspective view of another modified form of the advertising sign illustrated in FIGS. 1 through 3; and

FIG. 6 is an enlarged top plan view of FIG. 5.

We claim:

The ornamental design for an advertising sign, substantially as shown and described.
